UNITED STATES PATENT OFFICE.

GEORGE L. WARREN AND EDWARD J. TIESING, OF NEW HAVEN,
CONNECTICUT.

PARALLEL-RULER.

SPECIFICATION forming part of Letters Patent No. 600,758, dated March 15, 1898.

Application filed June 23, 1897. Serial No. 641,941. (No model.)

To all whom it may concern:

Be it known that we, GEORGE L. WARREN and EDWARD J. TIESING, citizens of the United States, and residents of New Haven, county 5 of New Haven, and State of Connecticut, have invented certain new and useful Improvements in Parallel-Rulers, of which the following is a full, clear, and exact specification.

Our invention relates to draftsmen's utensils, more particularly to rulers, adapted also for other purposes; and it consists of the herein-described device for setting a movable ruler-blade at any desired angle to another stationary, provided with means for affixing 15 the same upon the surface to be ruled, and for shifting the movable blade at adjustable equidistant steps, while at the same time its angular position in relation to the stationary blade is maintained unchanged.

20 Our invention is illustrated in the accompanying drawings, wherein—

Figure 1 is a rear elevation of our parallel-ruling device; Fig. 2, a top view, and Fig. 3 an end view, thereof. Fig. 4 is a sectional view on line 4 4, indicated in Fig. 2. Figs. 5 and 6 are similar sectional views showing the relative positions of the several parts at different stages of the operations. Fig. 7 is an elevation of a clamping-plate.

30 Our parallel-ruler consists of the stationary blade A, rod B, rigidly secured thereto in brackets a, support C, provided with a bifurcated protractor-head C', a movable blade E, with pointer e pivoted thereto, the clamping 35 and shifting devices o and p, and gage D.

Blade A is provided with prongs j, fixing it in position. Brackets a are secured to the stationary blade A by screws b in such position as to hold the rod B exactly parallel to 40 the edges d and d'. On this rod B slides support C, having an outward-projecting circular head C', provided on its edge with graduations indicating angles from zero to one hundred and eighty degrees. Head C' is bifurcated, and strip h inserted in the slot is pivoted to it by screw k. Pointer e is rigidly secured to the strip h, its apex being in close proximity to the graduated edge of the head C'. 45

Blade E is secured to strip h by screws h' in such position that the pointer e will always 50 indicate its angular deflection from the edges d and d' of the stationary blade A. Thus by using pointer e in connection with the graduations of the head C' the oscillating ruler E can be set at any desired angle to the stationary blade. 55

Support C consists of a base-plate f and standards l, made integral therewith and provided with corresponding bores fitted closely upon the rod B. Between the standards l 60 and exactly in their axial line is provided slot m, extending over the whole space between the standards l. Recesses n, one on each end of the base-plate outside of these standards l, are in the same line. Clamping- 65 plates o are slid on rod B between the standards l, and spring s presses them apart against the standards l, holding them normally in vertical position. Their lower ends are set in the slot m and slide therein. Rod B passes 70 through apertures o' of these clamping-plates, which are slightly larger than its sectional area to permit setting of these plates in position as shown in Fig. 5. The edges of these apertures o' clamp tightly the rod when plates 75 o are held in such inclined position. Plates p are similar in shape and construction to the clamp-plates o. They are slid on the rod and their ends are set in recesses n on the ends of the base-plate f. These clamping- 80 plates are, however, normally held in inclined position in relation to the rod B by the springs q, slid on the rod between the plates and the standards l. They are inclined oppositely to each other and thereby lock support C upon 85 rod B, preventing its motion in either direction. Blade E, pivoted to the head of support C, is thus held securely against longitudinal displacement in relation to the stationary blade A, though the clamping of the 90 support C does not prevent the swinging of blade E around the rod B. Support C may be freely moved on rod B when the clamp- 95 ing-plates p are pressed toward the standards l in the manner indicated in Fig. 6. Ruler-blade E may be fixed in any position to the

support C by screw *k*, and thus by shifting the support parallel lines may be drawn any distance apart, this distance being only limited by the length of the rod B.

5 More often it is required to draw parallel lines (such as in shading of surfaces in drawings) equidistantly from each other. This is accomplished by the coöperation of brake-plates *o* and gage D in the following manner:

10 We have already explained that when the clamping-plates *p* are pressed toward each other, as indicated in Fig. 6, the support C may be moved along the rod B at will and that plates *o* clamp rod B when they are set 15 against it in an inclined position. Gage D is set between the plates *o* and is provided with a downward-projecting guide *r*, fitted into the slot *m*, and with upward-bent flanges *v* on both sides. When either of these flanges 20 abuts against one of the plates *o*, it will press the edge of its aperture against the rod B and thereby arrest the motion of the support C. If the one of the plates *o* standing in the direction of the contemplated motion of the 25 support C is held to the rod B while the support C is moved forward, the motion of the support will be arrested when the flange *v* of the gage reaches it. Thus the length of the motion of the support C upon the rod B may 30 be varied by increasing or diminishing the distance between the flange of the gage and the corresponding plate *o*. Gage D is pointed and there is a scale *u* engraved upon the base-plate of the support C in such position that 35 the point *t* of the gage D will indicate this distance upon the scale. Gage D is provided with a slotted arm *y* and is secured in position by screw *w*, passing through the slot *x* into the standard *l*. Gage D may thus be ad- 40 justed in any position between the plates *o*. Scale *u* may be divided into fractions of inches or of any other unit of measures.

When it is required to draw parallel lines equidistantly from each other, the gage D is 45 set to indicate on the scale *u* the distance at which said parallel lines are to be drawn, and then the support C is moved by applying the index or middle finger of one hand to one plate *o*, (according to the direction the sup- 50 port is to be moved,) and then with the thumb of the same hand applied to the opposite plate *p* the support is moved until the flange *v* of the gage abuts against the plate *o*. This stops the motion of the support C on rod B 55 and when the hand is removed from the plates *o* and *p* or the pressure released springs *s* and *q* return them to their normal position. The ruler E will then be advanced exactly the re- 60 quired distance, as indicated on the scale *u*, and held there by the clamping action of plates *p*, as explained above. When the line is drawn, a similar operation will move the blade E an equal distance farther. When the support reaches the other end of the rod 65 B, it may be returned without stopping to its

starting-point in the manner described, or the gage D may be reset and the parallel-ruling proceeded with in reversed direction, the support C being shifted in the same manner.

Screws *k* and *w*, fixing the ruler-blade E 7c and the gage D in adjusted positions, are operated by pins *k'* and *w'*, respectively. They may, however, equally well be made with square or polygonal heads and operated by a key or otherwise. 75

We claim as our invention and desire to secure by Letters Patent—

1. A parallel-ruler comprising a stationary blade, a rod fixed in standards, secured to the stationary blade; a support, sliding on 80 the rod, and a circular head integral with the support; a movable blade, pivoted to the head; fixed clamping-plates, slid on the rod and having their ends engaged in recesses, provided in the base-plate of the support; 85 springs, set on the rod between the standards of the support and the fixed clamping-plates and holding them in their normal, clamping positions, locking the support to the rod.

2. A parallel-ruler comprising a stationary 90 blade, a rod fixed in standards, secured to the stationary blade; a support, sliding on the rod, a slot provided in the base of the support, parallel to the fixed rod, a head integral with the support, and projecting be- 95 yond the edge of the stationary blade, and a movable blade pivoted to the head; fixed clamping-plates, slid on the rod and having their ends engaged in recesses provided in the base-plate of the support; springs, set on the 100 rod between the standards of the support and the fixed clamping-plates, and holding them in their normal clamping positions, locking the support to the rod; movable clamping- 105 plates, slid on the rod between the standards 110 of the support and having their ends guided in the slot, a spiral spring, slid on the rod be- 115 tween the movable clamping-plates and holding them normally at a right angle to the fixed rod, and an adjustable stopping device se- 120 cured to the support between the movable clamping-plates.

3. The combination of a fixed rod, a sup- 115 port, suspended on the rod, spring-actuated clamping-plates, fixed in the support; mov- 120 able clamping-plates, slid on the rod between the standards of the support, and having their ends engaged in a slot, provided in the base of the support, a spiral spring, slid on the rod between the movable clamping-plates and holding them normally at a right angle to the 125 rod, and of a stopping device, secured to the support between the movable clamping-plates.

4. The combination of a fixed rod, a sup- 125 port, suspended on the rod, spring-actuated clamping-plates, fixed in the support, mov- 130 able clamping-plates slid on the rod between the standards of the support and having their ends engaged in a slot provided in the base

of the support, and parallel to the axis of the fixed rod; a spiral spring, slid on the rod between the movable clamping-plates and holding them normally at a right angle to the rod, 5 and of a gage adjustably secured to the support between the movable clamping-plates.

In witness that we claim the improvements described in the foregoing specification we

have signed our names in the presence of two subscribing witnesses.
